BRUSH FOR USE IN FLOOR PROCESSING APPARATUS

Walter S. Finnell, Elkhart, Ind.

Original application July 13, 1949, Serial No. 104,500. Divided and this application April 19, 1951, Serial No. 221,899

2 Claims. (Cl. 15—171)

1
This application is a division of the copending application Serial Number 104,500, filed on July 13, 1949, and relates to a Brush for Use in Floor Processing Apparatus, and more particularly to a brush having bristles and rubber scouring members. Such brushes may be used for any purpose and are particularly useful in connection with floor processing apparatus as disclosed in the copending application, Serial Number 81,035, filed on March 12, 1949, now U. S. Patent No. 2,600,233.

An object of the invention is to produce a long wearing brush.

Another object is to produce a brush of the class described having both bristle and rubber scouring members whereby the efficiency of the brush is increased as compared to brushes having only bristles or rubber members.

Another object is to provide an improved mounting for a brush of the character described whereby the brush is evenly and quickly applied to rotary floor treating apparatus of any type, such for example, as that described in the aforesaid copending application.

A further object is to provide a resilient mounting for a brush of the character described whereby the brush may automatically adjust itself to uneven surfaces to which it is applied.

Other objects and advantages will be apparent from the following specification and accompanying drawings wherein, by way of illustration, the invention is applied to a brush for floor treating machines.

It will be understood, however, that details of construction can be varied within wide limits, the invention being as defined in the appended claims.

In the accompanying drawings:

Figure 1 is a side view of a brush and its mounting embodying the invention;

Figure 2 is a sectional view of the brush only, on the line 2, 2, Figure 1;

Figure 3 is a sectional end view of Figure 1 on the line 3, 3, thereof;

Figure 4 is a fragmentary view of the bottom of the brush shown in any of the figures, showing the staggered arrangement;

Figure 5 is a plan view looking down on the rotary member of a floor treating machine equipped with the brushes and mountings therefor shown in the preceding figures; and

Figure 6 is a sectional view on the line 6, 6, Figure 5.

Referring to Figure 2 the numeral 10 denotes a center block of wood or other suitable material

which extends lengthwise of the brush and which may contain a plurality of tufts of bristles 11, 12 arranged in rows or in any suitable manner, and secured in the block in any suitable way.

Placed on each side of block 10 are a plurality of flat separate strips of rubber material such as may be cut from old tire casings or the like.

The strips comprise alternate layers of cord and of gum rubber vulcanized together whereby the gum enters between the cords and secures the cords of the respective layers to one another and secures the layers into a mass. In the layers the cords extend diagonally or on a bias, and the cords of one layer are arranged to extend crosswise or in directions intersecting the direction in which the cords of the adjacent layers extend. The cords and the rubber gum being vulcanized into a mass, a tough resilient structure is provided which is excellent for this purpose.

The two sets of flat strips are designated 13, 14 in the drawings, and while 6 strips in each set are shown, it will be understood that any lesser or greater number may be used.

Each strip is transversely slit as indicated at 15 whereby a plurality of comb-like teeth 16 are provided extending downwardly to the clamp members 17, 18 as shown.

Preferably the assembly of the steps is such that the teeth 16 are staggered as shown in Figure 4, wherein the teeth 16 in one row span the spaces 15 in the adjacent row. This arrangement permits a solid yet yielding surface for engagement with the surface to be cleaned.

All the rubber strips are perforated together with block 10 and are spanned by the clamp members 17, 18 which are also perforated to receive screws 19 which extend through the entire assembly which is drawn together and clamped by nuts 20. To prevent uneven wear the rubber strips can be laid up with the ply of the cords therein running in opposite directions as indicated by the shading in the sectional figures. This also causes the teeth 16 when subjected to pressure to tend to move in opposite directions in each strip.

No acid dip or other processing is necessary to pre-form teeth 16, and the brush is ready for use when assembled as above described.

The complete brush as above described can be used for many purposes for which brushes are commonly used and has good wearing qualities, as compared with all-bristle or all-rubber brushes. The rubber gives a scraping or scour-

ing action and the bristles penetrate small cracks, etc., too small for the teeth 16 to enter. The result is a better, quicker action than heretofore obtained.

Referring to Figures 1 and 3, the brush above described has an extension member 21 secured to the top of clamp 18 in any suitable manner or by welding, and extending outwardly from this member and secured thereto by screws 22 or in any manner is the U-shaped spring 23 having the downwardly extending projection 24 forming a stop as best seen in Figure 1.

Spring 23 is secured in any suitable manner as by bolts 25 to the mounting plate 26. Also suitably secured to the clamp 18 is a guide member 27 of any suitable shape to cooperate with the fixed member 28 suitably secured to the plate 26.

As best seen from Figure 1, the brush is now resiliently mounted on plate 26 and is urged downwardly therefrom by its own weight plus spring 23, so that it may yield and move perpendicular to the surface it engages. The stop 24 limits the compression that can be applied to the U-spring.

A plurality of the brushes, each mounted as above described, can be assembled on the plate 26 as indicated in dotted lines, Figure 5. The plate is mounted by means of screws 29 on a spider 30 which is rotated by any suitable means (such as the device shown in the aforesaid pending application) in the direction of the arrow.

Water may now be supplied to the rotating brushes via pipe 31 and will fall downwardly through the openings 32 in the spider 30, and impinge on the surface being cleaned.

The brushes being placed as shown, tend to urge the water inwardly, sweeping it under the brushes and keeping it from flowing radially in all directions. Obviously, by setting the brushes at various angles, the distribution of the water can be regulated.

Each complete individual brush assembled and mounted as above described, is indicated in Figure 5 by the numeral 33.

It will be seen that each individual brush forms a complete unit having a framework and that the spring member 23 is secured to one of the framework and the guide member 27 to the other end thereof, and that by removing screws 25, the brush units may be easily removed from the mounting plate 26.

What is claimed is:

1. In a brush for use in a floor processing

apparatus, a center block having a plurality of bristles secured thereto and extending freely therefrom, a plurality of strips of rubber material positioned at and overlying each side of said block, clamp members overlying the outside surfaces of said rubber strips, one of said clamp members extending over the back of said brush and overlying the portion of said center block from which said bristles depend, said strips extending freely beyond said block and clamp members, said strips being transversely slit from their outer extremities inwardly to said clamp members to form comb-like teeth, and means passing through said block, strips and clamp members for securing same together to form a brush.

2. In a brush for use in a floor processing apparatus, a center block having a plurality of bristles secured thereto and extending freely therefrom, a plurality of strips of rubber material positioned at and overlying each side of said block, clamp members overlying the outside surfaces of said rubber strips, said strips extending freely beyond said block and clamp members, said strips being transversely slit from their outer extremities inwardly to said clamp members to form comb-like teeth, and means passing through said block, strips and clamp members for securing same together to form a brush.
